United States Patent Office

Des. 183,493
Patented Sept. 9, 1958

183,493

FRUIT AND FLOWER CLIPPER

Anthony Piazza, Hicksville, N. Y.

Application March 12, 1957, Serial No. 45,226

Term of patent 7 years

(Cl. D35—2)

Fig. 1

Fig. 2

Fig. 3

Fig. 1 is a perspective view of a fruit and flower clipper embodying my new design;

Fig. 2 is a view similar to that of Fig. 1 but showing the device in open position; and

Fig. 3 is a perspective view opposite to that of Fig. 1.

I claim:

The ornamental design for a fruit and flower clipper, as shown.
